LUBRICATOR FOR PRESSURIZED FLUID

John C. Taylor, Denver, Colo., assignor to
C. A. Norgren Co., Littleton, Colo.

Filed July 17, 1972, Ser. No. 272,164

Term of patent 14 years

Int. Cl. D23—01

U.S. Cl. D23—3

FIG. 1 is a perspective view of a lubricator for pressurized fluid showing my new design;

FIG. 2 is a side elevational view thereof;

FIG. 3 is a top view thereof;

FIG. 4 is a bottom view thereof; and

FIGS. 5, 6 and 7 are additional side elevational views thereof.

I claim:

The ornamental design for a lubricator for pressurized fluid, as shown.
